GAME PIECE SUPPORT AND PROCESS OF USING THE SAME

Filed Oct. 17, 1927

INVENTOR:
William L. M. Clark
by Carr, Hall & Gravely,
HIS ATTORNEY.

UNITED STATES PATENT OFFICE.

WILLIAM L. M. CLARK, OF ST. LOUIS, MISSOURI.

GAME-PIECE SUPPORT AND PROCESS OF USING THE SAME.

Application filed October 17, 1927. Serial No. 226,655.

My invention relates to game piece supports, particularly to such devices intended for use in connection with games in which the pieces are small blocks with one face marked to indicate the nature of the piece in the game. The principal object of the invention is a support in which the pieces may be held so as to be easily visible to the player to whom they belong but concealed from the view of the other players, in which the pieces may be easily arranged for the play and in which individual pieces may be easily grasped for play.

The invention consists in the game piece support and process of using the same and in the parts and combinations and arrangements of parts hereinafter described and claimed.

In the accompanying drawing,

Fig. 1 is a perspective view of the support 20 with its hinged members spread out flat and the game pieces arranged face down on one portion thereof,

Fig. 2 is an end view showing the hinged members folded together to hold the pieces,

Fig. 3 is an end view showing the support arranged on edge ready to be opened out for use in the play, and

Fig. 4 is a perspective view showing the device opened out or unfolded supporting the pieces for play.

A preferred use of the invention is in playing bridge or other card games using pieces 1 or "tiles" consisting of small blocks of wood, composition or other suitable material one face of which has the nature of the piece marked thereon. The drawing illustrates faces representing ordinary playing cards. The device may be used in connection with Mah jongg or other games using tiles.

40 A strip of metal 2 or other material has a flange 3 along one edge adapted to support the edges of the game pieces. Said game pieces rest against the inclined body of the strip 2.

The upper portion 4 of the strip 2 is angularly disposed with reference to the body thereof, being bent along a line 5 at about the upper edges of the game pieces 1. Thus when the support is in use in a game, the upper portion 4 of said strip is disposed substantially vertically and constitutes a shield that

conceals the pieces 1 from the view of other players.

Said strip 2 and a second strip 6 are hinged 55 ly secured together by means of a pintle 7. When said strips are unfolded or opened out as nearly back to back as possible, the support is in position to hold the game pieces for play, as shown in Fig. 4. The strip 6 constitutes a brace for the strip 2, the two members forming substantially an inverted V.

60 The strip 2 may be provided with end flanges 8 to prevent tiles from slipping off the ends of the strip 2 if it should be tilted.

In the preferred process of using the support, the pieces are placed by the player face 65 down on the plain strip 6 of the hinge, as shown in Fig. 1. After the pieces are all in place on said strip 6, the strip 2 with the edge flange 3 may be folded over on the plain strip 6 as shown in Fig. 2, the bent portion 4 being 70 at such an angle that the body of said strip 2 lies flat against the game pieces 1. The support is then turned into the position shown in Fig. 3 with the edge flange 3 resting on the table. Then the plain strip 6 may be folded 75 up and over into its supporting position as shown in Fig. 4. This puts the pieces face up ready for the player.

The above described support makes it 80 makes it easy to handle game pieces and play them, it conceals the pieces from the view of other players, it is simple and inexpensive and it is easy to use.

What I claim is:

A game piece support comprising a plain strip adapted to receive game pieces and a 85 strip having a flange along its edge and having an angularly disposed portion hinged to said plain strip whereby said flanged strip is foldable on said plain strip with its flange overhanging said game pieces to hold them in position on said plain strip and when said flanged strip is placed inclined on edge and said plain strip unfolded, the pieces are supported on said flanged strip with their opposite faces exposed.

90 Signed at St. Louis, Missouri, this 14th day of October, 1927.

WILLIAM L. M. CLARK.
